UNITED STATES PATENT OFFICE.

HENRY DAVID MILLER, OF LAWTON, AND SAMUEL BUDD LIPPINCOTT, OF OKLAHOMA,
OKLAHOMA.

AUTOMATIC FIRE PREVENTER AND EXTINGUISHER.

1,266,034.

Specification of Letters Patent. Patented May 14, 1918.

Application filed June 12, 1917. Serial No. 174,277.

To all whom it may concern:

Be it known that we, HENRY DAVID MILLER and SAMUEL BUDD LIPPINCOTT, citizens of the United States, and residents of Lawton, in the county of Comanche and State of Oklahoma, and Oklahoma city, in the county of Oklahoma and State of Oklahoma, respectively, have invented new and useful Improvements in Automatic Fire Preventers and Extinguishers, of which the following is a specification.

Our invention is an improvement in automatic fire extinguishers, and has for its object to provide mechanism especially adapted for use with oil tanks, or in other inclosed spaces for preventing the igniting of the oil or material in said inclosed spaces, wherein means is provided for generating carbon dioxide gas and for discharging it into the tank or other inclosure, the said means being normally inoperative, and controlled by electric discharges, or by rise of temperature above a predetermined point in the tank or inclosure.

In the drawings:

Figure 1 is a diagrammatic view, with parts in section, of one embodiment of the invention;

Fig. 2 is a similar view of another embodiment;

Fig. 3 is a sectional view of a circuit closing device.

In the embodiment of the invention shown in Fig. 1, the tank 1 is provided with a gas discharge pipe 2, leading to the ground, and to a suitable point of discharge, and having interposed therein a pressure valve 3, which is designed to permit the escape of the gas and prevent the entrance of air to the tank.

A suitable container 4 is arranged at a distance from the tank, the said container being adapted to hold a strong solution of sodium bicarbonate, and within the container is arranged a bottle or jar 5 which is provided with two necks 6 and 7, respectively. A pipe 8 extends into the neck 6, and the neck 7 is closed by a loose acid-proof cap 9. This pipe 8 extends into a closed receptacle 10 which is arranged above the container 4, and the pipe 8 has an enlargement 11 within the receptacle. A water tank 12 is supported above the receptacle 10, and the said tank 12 has a discharge pipe 13 leading

from its bottom, and extending into the receptacle 10, and opening into the enlargement 11 of the pipe 8.

A fusible plug 14 closes the discharge end of the pipe 13, so that under normal conditions no water will flow from the tank into the bottle 5. This bottle is adapted to contain sulfuric acid, and it will be obvious that when water passes into the bottle, under conditions to be presently described, the cap 9 will be displaced, and the dilute acid will flow into the bicarbonate solution, and carbon dioxide will be generated.

A discharge pipe 15 for the carbon dioxide leads from the top of the container 4, and opens into another pipe 16 intermediate the top and bottom of the tank. This pipe 16 extends through the top of the tank, and is provided with a cross 17 within the tank, the arms of the cross having openings for permitting the gas to discharge into the tank above the level of the oil.

The fusible plug 14 is intended to be fused by the flame of a gas burner 18 which is arranged within the receptacle 10 and is supplied with gas by a suitable pipe 19, a controlling valve 20 being provided for controlling the supply of gas to the burner. The burner is designed to be ignited by an electric spark, and a spark gap is provided just above the burner and in position to ignite the gas when a spark jumps the gap. The spark gap is between the electrodes 21 and 22 which are supported by the walls of the receptacle 10, the said electrodes extending from opposite sides of the receptacle and being insulated from the wall of the receptacle. When the gas at the burner is ignited by a spark at the spark gap, the pipe 11 will be heated and the plug 14 will be fused. The electrode 22 is grounded, as indicated at 23, and the electrode 21 is connected with an aerial 24 composed of a series of wires supported by cross arms 25 on poles 26 arranged at opposite sides of the tank, the arrangement being such that the aerial is stretched above the tank.

It will be obvious that at the approach of a thunder storm, static electricity will be discharged by the aerial through the lead wire 27 which connects the same with the electrode 21, and as the sparks pass the gap between the electrodes 21 and 22 the gas will

be ignited. The heat generated by the burner will fuse the plug 44, and water will discharge from the tank 12 into the bottle 5. A dilute solution of sulfuric acid will 5 displace the cap 9 and will flow into the solution of sodium bicarbonate. Carbon dioxide gas will be generated, and will flow through the pipes 15 and 16 and the cross 17 into the tank above the oil, forcing out the 10 gas and air in the tank through the pipe 2 and diluting the gas and air to such a point that it will not be ignited by lightning.

In cases where it is desired to discharge a mixture of water and carbon dioxide, the 15 pipe 15 may be connected with the bottom of the container 4. In order to insure that the water will flow from the tank 12 into the bottle regardless of the pressure in the container 4, the discharge pipe 15 is connected to the tank 12 by means of a pipe 30, and a valve 31 is interposed in said pipe for controlling the same.

The pipe 15 is also provided with a valve 32 for permitting the same to be closed 25 during cleaning and the like. The container 10 has an outlet 33 for the gases of combustion, and the receptacle 4 has an opening in its top which is closed by a cover 34.

In Fig. 2 is shown an arrangement where- 30 in the device is electrically controlled from a suitable source of electric energy as, for instance, a battery. In this arrangement the receptacle 35 for the bicarbonate solution has therein a two-necked bottle 36, a pipe 37 corresponding to the pipe 8 of Fig. 1 leading into one neck, while the other is closed by a loose cap 38. The pipe 37 has the enlargement 38 in the container 39, and the pipe 40 from the water tank 41 opens into 40 the enlargement, extending through the wall of the container 39. This pipe 40 has a fusible plug 42 in the enlargement, and an electric heater 43 is arranged below the enlargement.

45 Circuit closers 44, shown more particu- larly in Fig. 3, are arranged in circuit with the heater 43. These closers consist of bulbs 44^a containing mercury, and one lead wire 45 of the circuit extends into the mercury. 50 The other lead wire 46 is connected with a contact rod 47 which is adjustably held in the top of the bulb by a set screw 48. This rod does not normally contact with the mercury, but is adapted to contact therewith 55 when the mercury is subjected to a predetermined heat. The bulb has adjacent thereto a scale, indicated at 48^a, for indicating the temperature, and the rod 47 may be arrested for contact with the mercury at any de- 60 sired point.

With the above described arrangement, a number of tanks or other inclosures may be protected, one of the circuit closing devices 44 being arranged in each tank or inclosure.

65 It will be obvious that when any circuit

closer is operated to close the circuit through the heater 43, the said heater will fuse the plug 42 and water will flow into the bottle 36, diluting the acid which will pass out, displacing the cap 38 and carbon dioxide will be 70 generated.

A signal 49, in the present instance, a bell, is branched on to the circuit 45-46, of each circuit closer, as indicated at 50, and it will be noticed that the arrangement is such that 75 each signal is in parallel with the circuit closer. Either or both branch circuits 50 may have interposed therein a battery, as indicated at 51. Where more than one tank or room is to be protected, a heater casing 80 indicated at 52 is provided for each tank or room. Into these casings pipes 53 extend, said pipes corresponding to the pipe 15 of the construction of Fig. 1, that is, the said pipes deliver carbon dioxide to the tanks or 85 rooms.

Each pipe 53 opens into an enlargement 54 of a pipe 55 which extends from the receptacle 35. Each of the pipes 55 carries a fusible plug 56 in the enlargement 54, and 90 an electric heater 57 is arranged below each enlargement within the casing. These heaters are branched on to the circuit 45-46, as indicated at 58, so that when a circuit closer 44 is operated the plugs 56 will be fused, 95 thus opening a direct way for the carbon dioxide from the receptacle 35 to the respective rooms or tanks. The plugs 56 are arranged to fuse at a lower temperature than the plug 42, and the heaters 57 generate more heat 100 and more quickly, so that the carbon dioxide pipes 53 are open to the fire when the carbon dioxide generator begins action. These heaters 57 are in parallel with the heater 43, with the circuit closers and with the signals 105 49.

Suitable sources 59 of electric energy are arranged within the circuit. The signals 49 may be arranged wherever desired to give the alarm.

110 The improved device shown in Fig. 1 provides for a continuous reduction of the amount of oxygen in the tank and of the amount of natural gas, supplying carbon dioxide gas whenever there is danger from lightning. The improvement provides for automatically flushing the tank with carbon dioxide gas when an electric storm approaches. The aerial wires, by continually gathering the static charges as they form, and discharging them to the earth, prevent sufficient static electricity gathering above the tank to cause a stroke of lightning.

115 The device of Fig. 2 is especially desirable for buildings, because of the fact that there is no injury by water, the only damage being that due to the fire.

120 It will be understood that sodium carbonate may be used instead of sodium bicarbonate, if desired, and a solution of so- 130

dium bicarbonate may be substituted for water in the tank 12 of Fig. 1 or in the tank 41 of Fig. 2.

An oil lamp may be used if desired, and 5 the electrical connections and grouping of heater 43 and heater 57 may be changed, so that the circuit closer 44 may close the circuit for as many heaters 57 as desired, or 10 may be changed so that each circuit closer 44 may operate the heater 43 and one or more heaters 57.

It will be understood that the device is primarily a fire preventer, being especially 15 adapted to prevent oil fires, but arranged to extinguish a fire if a fire should be started. It should also be understood that in both embodiments of the invention shown 20 in Figs. 1 and 2, the carbon dioxide generator is the same and the generated gas is used for the same purposes of flooding an inclosed 25 space to drive out the oxygen and discourage combustion. The only difference lies in the method of fusing the water plugs 14 and 56. In Fig. 1 the plug 14 is fused by the heat from the spark at the gap 21-22, while in Fig. 2, the plug 42 is fused by the heating coil 43.

The apparatus in Fig. 1 is adapted to outdoor work since the illuminating gas from 30 the burner 18 must constantly escape. Obviously, this feature would be objectionable indoors. The arrangement shown in Fig. 2 is particularly adapted to indoors since there is not the objection of the escaping 35 gas. Here the fusion of the water plugs is thermostatically controlled.

We claim:

1. An automatic fire extinguisher for oil tanks comprising in combination, a receptacle 40 containing a solution of sodium bicarbonate and having an outlet delivering to the tank, a jar for sulfuric acid in the receptacle and having a discharge at its top delivering to the receptacle, a burner casing 45 provided with a burner, a pipe leading from the jar and extending into the casing above the burner, a tank of water having a discharge pipe leading into the last named pipe in the burner casing, said pipe being 50 normally closed by a fusible plug within the pipe from the receptacle, an electric circuit having a spark gap in the burner casing at the burner, an aerial above the tank, the circuit being connected at one end to the 55 aerial and grounded at the other.

2. An automatic fire extinguisher for oil tanks comprising in combination, a receptacle 60 containing a solution of sodium bicarbonate and having an outlet delivering to the tank, a jar for sulfuric acid in the receptacle and having a discharge at its top delivering to the receptacle, a burner casing 65 provided with a burner, a pipe leading from the jar and extending into the casing above the burner, a tank of water having a dis-

charge pipe leading into the last named pipe in the burner casing, said pipe being normally closed by a fusible plug within the pipe from the receptacle, and an electric circuit having a spark gap in the burner 70 casing at the burner.

3. An automatic fire extinguisher comprising a receptacle containing a solution of sodium bicarbonate and having an outlet delivering to the place where the fire is to be controlled, a jar for sulfuric acid in the receptacle and having a discharge at its top delivering to the receptacle, a water supply 75 delivering to the jar, a fusible plug normally closing the said supply, a gas burner for fusing the plug, and an electric circuit having a spark gap at the gas burner for igniting the gas.

4. An automatic fire extinguisher comprising a receptacle containing a solution of sodium bicarbonate and having an outlet delivering to the place where the fire is to be controlled, a jar for sulfuric acid in the receptacle and having a discharge at its top delivering to the receptacle, a water supply 85 delivering to the receptacle, a water supply 90 delivering to the jar, a fusible plug normally closing the said supply, a gas burner for fusing the plug, an electric circuit having a spark gap at the gas burner for igniting the gas, and a net-work of wires above 95 the tank and connected to the circuit.

5. An automatic fire preventer for oil tanks, comprising means normally inoperative for generating carbon dioxide gas and delivering to the space above the oil in the 100 tank, heat controlled means for actuating the generating means, and electrically controlled means for putting the heat controlled means into operation.

6. The combination with an oil tank, of means normally inoperative for generating carbon dioxide gas and delivering it to the tank above the oil therein, heat controlled means for actuating the generating means, and an aerial above the tank, said aerial being grounded, and electrically controlled means interposed between the aerial and the ground for operating the heat controlled means.

7. In a fire preventing device, the combination with an oil tank, an aerial arranged to gather a charge of static electricity from around the tank to protect the tank, and normally inoperative means affected by the gathering charge, for generating carbon dioxide gas and flooding the space above the oil in the tank.

8. In a fire preventing device, the combination with an oil tank, an aerial arranged to convey a charge of static electricity from above the tank, normally inactive means in communication with the space in the tank above the oil, for generating carbon dioxide gas, said means including a fusible water plug, a gas jet with normally flowing gas,

electrodes for the aerial, disposed between the gas jet and fusible water plug, and a housing for the jet, plug, and electrodes with an opening permitting the gas to normally escape to atmosphere.

9. In a device as described, means normally inactive for generating carbon dioxid gas and delivering the gas to the place where the fire is to be controlled, a device including 10 fusible means rendered active upon fusion,

for actuating said generating means, and an electric circuit including a heat producing means, operative to fuse the fusible means, upon energization of said electric circuit.
